UNITED STATES PATENT OFFICE.

JOHN W. BOUGHTON, OF PHILADELPHIA, PENNSYLVANIA.

AIRSHIP.

1,075,540.

Specification of Letters Patent.

Patented Oct. 14, 1913.

Application filed February 9, 1912. Serial No. 676,804.

To all whom it may concern:

Be it known that I, JOHN W. BOUGHTON, a citizen of the United States, residing in the city and county of Philadelphia, State of Pennsylvania, have invented a new and useful Airship, of which the following is a specification.

My invention consists of an improvement in an air ship embodying planes on the sides 10 of the frame thereof, and means for changing the angle thereof.

It consists also of a plane on the top of the frame and means for changing the angle thereof. By these means the flight of the 15 ship when propelled may be readily effected and controlled.

It consists further of the construction of the frame of the ship whereby the same is light, strong, durable and inexpensive.

20 The invention is satisfactorily illustrated in the accompanying drawing, but the important instrumentalities thereof may be varied, and so it is to be understood that the invention is not limited to the specific arrangement and organization shown and described.

Figure 1 represents a front elevation of an air ship embodying my invention. Fig. 2 represents a plan view thereof. Fig. 3 30 represents a side elevation thereof. Fig. 4 represents a front view of the frame of the ship. Fig. 5 represents a plan view of said frame. Fig. 6 represents a longitudinal vertical section of one of the side planes of the 35 ship.

Similar letters of reference indicate corresponding parts in the figures.

Referring to the drawings:—A designates the frame of the airship. This frame is disposed at the longitudinal center of the ship 40 and is composed of vertical bars A', transverse bars B, a transversely-extending bar C on the top of the frame, and longitudinally extending angle irons D, the bar C being rearward of the top bar B, the several members being bolted or riveted together forming a light, strong, durable and inexpensive structure. To the top bar B and the bar C is secured the plane C², which latter 45 thus occupies a central position on the ship.

E are vertical planes disposed upon opposite sides of the main frame A and on each are mounted the horizontal planes F which 50 are adapted to swing or rock on said vertical planes E and have pivotally connected with them the auxiliary frames G which

may be raised and lowered by suitable means, in the present case, the links or elbows H and the lever J, whereby the angles of said planes may be changed according to 55 the requirements of aviation. The side members of the vertical planes E are strengthened by brace rods e, as shown in Figs. 1 and 6, the same acting as stops to limit the descent of the planes F.

On the bars C', to the rear of the planes E, at the top of the frame A are the central and side transversely-extending planes K, and rearward of the same is the frame L on which is mounted the horizontal plane M 70 which has a pivotal connection with said frame L, so as to be capable of changing its angles according to requirements of aviation, the means employed for effecting such change being in the present case, the links N 75 which are connected with the rear of said plane M and the pulley P which latter is secured to the pivot of the front link N, and has passed around it the strap or belt Q which extends into the cabin, apartment, or 80 room R of the ship, said cabin being properly mounted on the frame of the ship.

S designates the propeller of the ship, the same being suitably mounted on the frame A and receiving its power by a motor 85 in the room R or elsewhere.

On the rear of the frame L is mounted the rudder T which is provided with means U for operating the same.

The planes F as is evident are adapted to 90 be moved simultaneously in the same direction, and when they are inclined downwardly and rearwardly, the ship will leave the ground in much less space than has been capable heretofore under present conditions 95 where small planes are used, and the whole lifting surface is opposed to the direction required to lift the ship from the ground. As said planes F are hinged at their front ends and adapted to be moved from their 100 rear ends, it takes less power to change the direction or angle of said planes than if hinged or pivoted at their middle portion. It will be seen also that but few levers are required to control the ship and all of the, 105 same may be operated in the cabin R which provides comfortable quarters for the aviator and other travelers, the bars of the frame supporting the same and other members of the ship being formed preferably of metal 110 thin and light but sufficiently strong for the purpose intended.

The planes C², K may be hinged so as to be angularly adjustable similar to the horizontal planes F. The latter resemble a box kite, the sides of the planes E in which said planes are mounted being covered and protected with plates $\frac{1}{4}$ of thin metal or other suitable material, as shown in Figs. 3 and 6. Additional vertical planes can be added at frequent intervals to protect the vacuum 10 over the planes when in motion.

Having thus described my invention what I claim as new and desire to secure by Letters Patent is,

1. In an airship, a frame, a stationary vertical plane thereon, a horizontal plane pivotally mounted on said vertical plane, an auxiliary frame movable on said vertical plane and means for raising and lowering said auxiliary frame.
2. In an airship, a frame, a stationary vertical plane thereon, a horizontal plane pivotally mounted on said vertical plane, an auxiliary frame movable on said vertical plane, means for raising and lowering said auxiliary frame, and means pivotally connecting said horizontal plane with the auxiliary frame.
3. In an airship, a central frame, stationary vertical planes mounted thereon, horizontal planes pivotally mounted on said vertical planes, auxiliary frames movable on said vertical planes, said horizontal planes being pivotally connected with the auxiliary frames and transversely extending planes to the rear of said vertical planes.
4. In an airship, a central frame, stationary vertical planes mounted thereon, horizontal planes pivotally mounted on said

vertical planes, auxiliary frames movable on said vertical planes, said horizontal planes being pivotally connected with the auxiliary frames and transversely extending planes to the rear of said vertical planes, and means for raising and lowering said auxiliary frames.

5. In an airship, a frame, a plane centrally disposed thereon, vertical planes in advance of the central plane and upon opposite sides of the frame and horizontal planes mounted on said vertical planes.

6. In an airship, a frame, a plane centrally disposed thereon, vertical planes in advance of the central plane and upon opposite sides of the frame and horizontal planes mounted on said vertical planes, and a central plane disposed between the vertical planes.

7. In an airship, a frame, a centrally disposed plane at the front thereof, a centrally disposed plane at the rear, vertical side planes at the front, horizontal planes mounted thereon, and auxiliary planes mounted to the rear of the vertical planes.

8. In an airship, a frame, a centrally disposed plane at the front thereof, a centrally disposed plane at the rear thereof, vertical side planes at the front, horizontal planes mounted thereon, auxiliary frames mounted to the rear of the vertical planes, and means for raising and lowering the auxiliary frames.

JOHN W. BOUGHTON.
